United States Patent Office

Des. 198,598
Patented July 7, 1964

198,598

DISPENSING CLOSURE FOR BOTTLES OR THE LIKE

Joseph Anthony Milenkevich, Cincinnati, Ohio, assignor to The Procter & Gamble Company, Cincinnati, Ohio, a corporation of Ohio

Filed Apr. 4, 1963, Ser. No. 74,291

Term of patent 14 years

(Cl. D58—26)

Fig. 1

Fig. 3

FIG. 1 is a top plan view of a dispensing closure for bottles or the like showing my new design.

FIG. 2 is an elevational view thereof.

FIG. 3 is a perspective view thereof.

I claim:

The ornamental design for a dispensing closure for bottles or the like, as shown.
